United States Patent Office

Des. 187,877
Patented May 10, 1960

187,877

HANDLE FOR CASSEROLE OR THE LIKE

La Gardo Tackett, Los Angeles, Calif., assignor to Schmid International, a division of Schmid Kreglinger, Inc., Boston, Mass., a corporation of Delaware

Application March 12, 1959, Serial No. 54,949

Term of patent 14 years

(Cl. D44—29)

Fig. 1

Fig. 3

Fig. 1 is a view in front elevation of one side of the handle for casserole, the reverse side being substantially the same as that shown, embodying my new design.

Fig. 2 is a view in side elevation, and

Fig. 3 is a cross sectional view taken along the line 3—3 of Fig. 1.

I claim:

The ornamental design for a handle for casserole or the like, substantially as shown.
